UNITED STATES PATENT OFFICE.

ISAAC F. BASSFORD AND MILES MAHAN, OF BUTTE CITY, MONTANA TERRITORY.

SNAP-HOOK.

SPECIFICATION forming part of Letters Patent No. 285,956, dated October 2, 1883.

Application filed August 2, 1883. (No model.)

To all whom it may concern:

Be it known that we, ISAAC F. BASSFORD and MILES MAHAN, of Butte City, in the county of Silver Bow and Territory of Montana, have invented certain new and useful Improvements in Snap-Hooks; and we do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of our improved snap-hook; and Figs. 2, 3, 4, and 5 are elevations of the same from three different sides, the two latter figures showing it open and closed.

Similar letters of reference indicate corresponding parts in all the figures.

Our invention has relation to snap-hooks; and it consists in the improved construction and combination of parts of a hook formed in a shape similar to the shape of the open link 25 commonly used in connecting two ends of a chain together, as hereinafter more fully described and claimed.

In the accompanying drawings, the letter A indicates a flat shank having a transverse slot 30 or perforation, B, for the insertion and fastening of the cord, rope, strap, or chain, to the end of which the hook is attached; and C indicates the rigid hook, which is integral with the shank and turned in a plane at a right angle to the plane of the shank. This hooked portion consists of a flat body, preferably triangular in shape, and the hook proper, D, which forms a part of an oval, the end of the hook being bent inward toward the body portion. The hinged hook E is of the same shape 40 as the rigid hook, and is hinged in a slot, F, in the upper end of the shank, its curved point pointing in the opposite direction to the point of the rigid hook, and its inner end, inside the pin, upon which it is hinged, is pointed, and bears against the inner sides of the free ends 45 of two flat springs, G and H, fastened at their inner ends upon the sides of the shank upon a pin, I, passing through the same, so that the

springs may be turned to the sides from bearing against the pointed end of the hinged hook, the spring G bearing against the rear edge of the hook, fitting with its end in a notch or recess, J, in the same, preventing it from being tilted too far back. The outside of the hinged 50 hook is provided upon its body portion with a projecting block, K, against the front edge of which the thumb of the person using the hook may press in pushing the hook open, admitting the ring or link upon which the hook is to be fastened, and the springs upon both sides will force the hook closed when the pressure upon the block is released.

If it is desired to have the hook open, the springs may be turned to a side, which will 65 release the hinged hook, allowing it to swing freely; and if the spring bearing into the notch upon the rear edge of the hinged hook is pushed to the side the hook may be thrown wide open and held in that position, the other 70 spring bearing against the end L of the hook, which is cut off obliquely, bearing, when closed, against the correspondingly-beveled inner end of the slot F, which construction prevents the hook from being pressed too far forward by 75 the spring bearing against its rear edge.

It is obvious that this hook may be used for any purpose for which a snap-hook may be used by making it of the necessary dimensions and strength, and by shaping the slot or perforation of a suitable shape for holding the strap, cord, rope, or chain to which it is to be attached.

Having thus described our invention, we claim and desire to secure by Letters Patent of 85 the United States—

1. A snap-hook consisting of a rigid hook having a shank adapted to be fastened to the object to be provided with the hook, and a hook hinged at its inner end to the rigid hook, 90 having its hooked end pointing in the opposite direction to the rigid hook, having a notch in the rear edge of its inner end, and bearing with its inner end, inside its pivotal point, against the free ends of two flat springs fastened upon the shank of the rigid hook, as and for the purpose shown and set forth.

2. The combination of the rigid hook hav-

ing a shank provided with a suitable slot or perforation, and bent in a plane at a right angle to the plane of the hook, and having its outer end curved toward its body portion, a 5 hinged hook hinged in a slot in the upper end of the shank of the rigid hook, having a block upon the outside of its body portion, having its outer end bent in the opposite direction to the rigid hook, having a notch upon the rear 10 edge of its inner portion, and bearing with the obliquely-cut end of the same against the correspondingly-beveled inner end of the slot in the end of the shank, and two flat springs bearing with their free ends against the edges of 15 the inner end of the hinged hook, and fastened

upon a pin passing through the inner ends and through the shank of the hook, as and for the purpose shown and set forth.

In testimony that we claim the foregoing as our own we have hereto affixed our signatures 20 in presence of two witnesses.

ISAAC FRANKLIN BASSFORD.

MILES MAHAN.
